UNITED STATES PATENT OFFICE.

HARRY HICKMOTT, OF BRENTWOOD, ENGLAND.

SLUICE-BOX AND BRIDGE.

SPECIFICATION forming part of Letters Patent No. 616,326, dated December 20, 1898.

Application filed January 25, 1898. Serial No. 667,914. (No model.)

To all whom it may concern:

Be it known that I, HARRY HICKMOTT, a subject of the Queen of Great Britain, residing at Weald Park, Brentwood, Essex county, England, have invented certain new and useful Improvements in a Combined Sluice-Box and Bridge; and I do hereby declare the following to be a full, clear, and exact description of the invention, such as will enable others skilled in the art to which it appertains to make and use the same.

This invention relates to treble sluices combined with a bridge; and it consists, essentially, of a waste-flood and ordinary water-slue arranged in one device at varying elevations leading from a fish-guard and having connected therewith a series of plugs with elongated stems adapted to be operated to open the various sluices and permit the water to flow thereinto.

The invention further consists of the details of the construction and arrangement of the several parts, which will be more fully hereinafter described and claimed.

One object of the invention is to provide a sluice which is adapted for use in running water off from a lake, pond, or other inclosure at varying levels and which may be employed for only partially drawing off the water or entirely draining the same from an adjacent point.

A further object of the invention is to simplify the construction and arrangement of such devices and render them more positive in their operation, as well as strong and durable and comparatively inexpensive in the cost of manufacture.

In the accompanying drawings, Figure 1 is a diagrammatic sectional view showing the improved sluice in position. Fig. 2 is a perspective view of the improved sluice. Fig. 3 is a top plan view of the same. Fig. 4 is a longitudinal vertical section taken through the center of the device. Fig. 5 is a trans-

verse vertical section.

Referring to the drawings, wherein similar numerals are employed to indicate corresponding parts in the several views, the numeral 1 designates a base, from the corners of which rise standards 2. The base and the

lower portions of the standards are surrounded by boxing 3, and also secured to the said standards above the boxing on the sides and inner end are slats 4, which may extend only partially over the length of said standards or 55 be continued entirely to the top of the same for the purpose of forming a fish-guard to prevent the escape of fish or aquatic animals in draining a pond, lake, or basin. On the top 60 of the standards are cross-sills 5 and 6, which 65 extend transversely of the device and are tied on the ends by metallic straps or analogous devices 7. The sill 5 has a pair of slots 8 extending therethrough vertically, and spaced apart a suitable distance and intermediate of 70 the said slots and projecting outwardly therefrom is a metallic guide 9, which is slotted and disposed horizontally, the said guide being connected with its support by an angular bend and elevated above the level of the sill 75 5. In the sill 6, at the center thereof, is a vertical slot 10, and to one side of the said slot is a counter-slot 11, over which is mounted a winding-shaft 12 in bearings 13. One end of the winding-shaft has keyed thereon a ratchet-wheel 14, which is engaged by a stop-pawl or analogous device 15, pivotally attached to the adjacent edge of the said sill 6. The opposite end of the said winding-shaft 12 is enlarged and apertured, as at 16, and therein is 80 movably mounted a handle-bar 17.

Resting in a slot in the center of the base 1 is a single sluice-box 20, which is preferably located at about a level of seventeen feet under the surface of the water. The said sluice-box is slightly inclined to give a fall to the water flowing therethrough, and in the rear of the upper portion thereof is a feed-opening 21, adapted to be engaged by a stop-plug 22, having an elongated stem 23 rising therefrom 85 and passing upwardly through the slot 10 in the sill 6. Secured to one side of the stem 23 is the lower end of an elevating-chain 24, which has its upper end attached to the winding-shaft 12, and by means of the said chain 90 and shaft the said stem, as well as the plug at the lower end thereof, may be drawn upwardly to open the feed-opening 21 in the said sluice-box 20. As an auxiliary to sustain the shank 23 in elevated position it is provided 95 100

with openings 25, in which is adapted to be removably fitted a locking-pin 26, secured by a chain 27 on an adjacent part of the said sill 6. The reason the winding-shaft and chain 5 are employed in connection with the shank 23 and plug 22 is that in a large structure considerable resistance would be offered from various causes in clearing the said plug from the feed-opening 21 in the said sluice-box 20, and 10 while it might be possible for a single operator to elevate the said shank and plug under favorable conditions it might require under other conditions a greater expenditure of power than could be applied solely through 15 manual exertions.

Resting on the top of the sluice-box 20 and extending transversely thereof are space-blocks 28, on which is secured a double sluice-box 29, having a central dividing-partition 30 20 and two rear feed-openings 31 in the upper part thereof. These feed-openings are adapted to be engaged by stop-plugs 32, having shanks 33 rising therefrom and projecting upwardly through the slots 8 in the sill 5. These latter 25 plugs and shanks may be readily elevated by ordinary manual power, and for the purpose of holding the same elevated and keeping the feed-openings 31 clear the shanks 33 have openings 34 extending therethrough, which 30 are adapted to be engaged by locking-pins 35, loosely attached by chains 36 to the adjacent edge of the sill 5. Either one or both of the plugs 32 and shanks 33 may be elevated; but this will depend altogether upon the 35 conditions, and it may be found necessary under certain circumstances to only clear one of the openings 31. The double sluice-box 29 is to be preferably located about ten feet under the surface of the water.

40 Resting on a cross-brace 37, attached to the adjacent standards 2 and also on a bridge-block 38, rising from the top of the front portion of the sluice-box 29, is a single flood-slue 40 with a rear upper opening 41, adapted to be engaged by a plug 42, having an upwardly-projecting shank 43 extending through the guide 9, and the said shank has a transverse opening 44 therein, adapted to be engaged by one of the pins 35 or an analogous device to hold the plug 42 and shank 43 45 in elevated position. This flood-slue is intended to be located about three feet under the surface of the water.

Each of the shanks extending upwardly 50 from the plugs has on the upper end thereof a metallic loop 45, which is adapted to be used in elevating the said shanks and the plugs thereon, and in very large structures overhead mechanism can be attached to the said loops, 55 if desired, for the purpose of raising the parts to which they are connected.

On another cross-brace 46, at a higher elevation than that heretofore described and also on a transverse brace-beam or sill 47, are 60 a pair of independent oppositely-disposed waste-water sluices 48, which have their up-

per rear portions cut away to form feed-openings 49 and are intended to carry off the surplus water from a lake, pond, basin, or other inclosure at the level thereof, and thereby 70 maintain a desired uniform depth. Extending across the said waste-water sluices and from one to the other is a bridge 50 to permit easy passage from one to the other in the operation of the several parts, and it will be 75 observed in this connection that the sills 5 and 6 can also be employed for a similar purpose.

In applying the device in operative position it will be arranged, as shown in Fig. 1, 80 with the standards 2 and base 1 inside of the lake, pond, or basin, with which the device is used adjacent to an embankment or outflow-point formed at one side thereof. All of the 85 sluice-boxes will extend far enough into the basin, pond, or lake to have the openings thereof so arranged as to permit the easy flow of the water therethrough, it being observed that the said sluice-boxes are of different lengths, and, further, that they are all closed at 90 their inner ends. The waste-water sluices, it will be understood, are always operating, and in the event of an overflow through floods or surpluses of water due to other causes the 95 flood-slue 40 is intended to be opened, and in draining the water-inclosure a still greater depth the double sluice-box 29 is caused to operate. If it is desired to thoroughly drain the lake, the lowermost sluice-box 20 is 100 opened.

While these sluice-boxes have been described as being at specific distances below the surfaces, it will be understood that their depth of position may be varied in accordance with the use thereof, and it will be found that many 105 advantages will become apparent to those using the improved combined sluice and bridge other than those enumerated, and, further, that changes in the proportions, dimensions, and minor details of the construction might be made and substituted for those shown and described without in the least departing from the nature or spirit of the invention.

Having thus described the invention, what 115 is claimed as new is—

1. In a device of the character set forth, the combination of a fish-guard, a lower sluice-box entering the same, a flood sluice-box, upper waste-water sluices, a bridge extending 120 across the said waste-water sluices, each of these sluices except the waste-water sluices having upper rear feed-openings, and plugs having elongated stems removably engaging the said feed-openings, substantially as described. 125

2. In a device of the character set forth, the combination of a series of superimposed sluice boxes and plugs removably engaging the upper rear portions of the said sluice-boxes, substantially as described.

3. In a device of the character set forth, the combination of a series of sluice-boxes of

varying lengths, having openings in the upper rear portions thereof, plugs removably engaging the said openings and having elongated stems projecting above the upper surface of the device, and means for holding the said stems and plugs elevated, substantially as described.

In testimony whereof I affix my signature in presence of two witnesses.

HARRY HICKMOTT.
